UNITED STATES PATENT OFFICE

JOSEPH H. DICKINSON, OF LARCHMONT, NEW YORK, ASSIGNOR TO THE AEOLIAN COMPANY, A CORPORATION OF CONNECTICUT

EXPRESSION DEVICE FOR AUTOMATIC PIANOS

Application filed May 17, 1927. Serial No. 192,006.

My present invention relates to improvements in reproducing pianos which play music-rolls with automatically reproduced dynamics expression of the hand playing of skilled pianists. This improvement is a device operable at will by the user to vary the degree of loudness of the playing to suit the conditions in which the instrument is placed, namely, whether it be in a large or small room or whether the music is to be used for dancing or merely for the pleasure of listening to it. Also, individuals differ in acuteness of hearing, some preferring that the rendition be relatively soft, others preferring it louder. The device is also useful and operable with delicate adjustment thereof by the user while the instrument is playing, to prevent the instrument from ciphering or failing to play all of the notes in pianissimo passages, which may happen in humid weather due to the swelling and consequent sticking of the parts of the piano hammer actions and related movable parts of the instrument which do not then work so freely as in dry weather. It is easy enough to vary the degree of loudness of the playing by varying the wind tension, but this affects unfavorably the operation of the automatic expression device and makes it alter the expression effects unfavorably. My present invention accomplishes the foregoing desirable results without limiting the expression device which at all times is under the unhampered control and operation of the dynamics expression music-roll perforations.

The annexed drawings show a preferred form of my invention in combination with one form of reproducing piano dynamics expression action, the parts being shown in diagrammatic form for purposes of simplicity.

In these drawings, Fig. 1 is said diagrammatic view of the said combination of devices embodying my invention; Fig. 2 is a horizontal section on the line 2—2 in Fig. 1 looking in the direction of the arrows; and Fig. 3 is a front elevation of a fragment of the tracker bar and music-sheet.

Describing now the illustrated devices embodying my invention, 1 is a box having a top 1^a and sides 1^b. The bottom of the box com-

prises a board 1^c hinged to the box at 1^d connected by flexible air-tight material secured to the edges of the board 1^c and the sides 1^b of the box, said board and flexible material thereby enclosing air-tight the bottom of the box and forming a pneumatic or bellows.

2 and 3 are cylindrical metal tubes extending through the sides of the box, 2 being connected with an air exhauster and 3 with the player action of an automatic piano, neither of which is shown. The player action will, of course, consist of the usual valve and striker-pneumatic action for selectively operating the piano hammer action from the note playing ducts 4^a of the tracker bar 4 when exposed by the note perforations 5^a of a music-sheet 5.

6 is a knife valve working across a port consisting of the mouth of the tube 2 inside the box 1. 7 is a rock shaft journalled in the sides of the box 1 extending horizontally across its interior. 8 is an arm secured to this rock shaft projecting at right angles thereto having a cylindrical pin 8^a projecting into a corresponding hole in the heel of the valve 6, whereby said valve is pivotally supported by its heel from said rock shaft arm 8. 9 is a link pivotally connected by its ends to the toe of said valve and the movable board 1^c of the regulator. 38 is the usual adjustable coiled tension spring connecting the movable board 1^c with the stationary part 39.

10 is an arm fixed on the rock shaft 7 similar to and paralleling the arm 8 except that the arm 10 is on the free end of said shaft outside of the box 1. 11 is a fixed support and 12 is a coiled tension spring connecting said support with the end of this arm 10. 13 is a rod or link connecting said end of the arm 10 with one end-board 14 of an accordion bellows 15 whose other end-board 16 is connected by a link 17 with a lever 18 pivoted at 18^a to any suitable stationary support to pivot in a direction towards and away from the regulator previously described. This lever 18 has a tapered free end 18^b between which and the stationary half-round part 19 is interposed the tapered or wedge-shaped end 20^a of another part 20 pivotally connected at 20^b to one arm of a bell-crank lever 21, the latter being pivoted

at 21^a to any suitable stationary support, not shown.

All of the mechanism thus far described will ordinarily be located below the piano keyboard, especially if it be an upright piano, and in any event will be located within the casing of the instrument. On the other hand, the fixed dial or scale 22 and the pointer 23 will be located outside the instrument at or near the keyboard in easy view and convenient to the hand of the user. This pointer 23 in the construction shown is one arm of a bell-crank lever pivoted at 23^a to any suitable stationary support, not shown. The dotted line 24 connecting the arms of the aforesaid bell-cranks 23 and 21, may consist, depending upon the particular installation, of a single link connecting said bell-cranks, or if in the particular installation said bell-cranks are out of alignment, may consist as will be well understood of a plurality of links and an additional bell-crank or cranks suitably arranged so that when the user of the instrument adjusts the pointer and the bell-crank 23 over the scale 22 in either direction, the motion of said pointer is correspondingly delivered by the intervening links and bell-cranks to the part 20 to slide its wedge-shaped end 20^a to a greater or less extent between the fixed support 19 and the end 18^b of the pivoted lever 18. It will be seen that the farther the part 20 is slid to the left in Fig. 1, the farther its wedge-shaped end 20^a will force the lever 18 to pivot downwardly, carrying with it bodily the entire accordion bellows; also the farther the heel of the valve 6 will be pulled downwardly with resulting greater exposure of the port 2 by the valve.

The tension spring 12 acts through the rod 13, accordion bellows 15 and the link 17 upon the lever 18 to cause its free end at all times to clamp the wedge end 20^a of the slide 20 against the stationary member 19 irrespective of whether said accordion bellows is fully expanded as in Fig. 1, or whether any or all of its sections or compartments be collapsed.

The particular accordion bellows shown has four collapsible compartments 15^a, 15^b, 15^c, 15^d, formed by flexible air-tight fabric glued to the edges of the end blocks 14 and 16 and to three intermediate blocks 25, 26 and 27, said compartments increasing in the extent of their vertical or axial collapse from 15^a to 15^d. In the particular bellows shown, compartment 15^b collapses twice as far as 15^a; 15^c collapses four times as far as 15^a and 15^d collapses eight times as far as 15^a.

The tracker bar 4 has four dynamics expression controlling ducts 4^b, each pneumatically connected through a valve means 28 with an accordion bellows compartment.

The valve means 28 are all alike, one of them

being shown in vertical section. This valve means is of the usual construction. The valve proper 29 alternately controls two ports, the atmosphere port 30 and the exhaust port 31, both connected by tube 32 with a compartment of the accordion bellows. The exhaust port 31 connects with the chamber 33 which is normally kept exhausted via the nipple 34. The valve 29 is supported on the pouch 35 of a pouch chamber 36, which latter is connected by a tube 37 with one of the aforesaid dynamics expression tracker ducts 4^b and is also connected by the usual bleed opening with the exhaust chamber 33.

As long as a dynamics duct 4^b is closed by a non-perforated part of the music-sheet, its valve means 28 is in the condition illustrated in Fig. 1 wherein its accordion compartment is on atmosphere by the atmosphere port 30 and hence is expanded as shown in the drawing. On the other hand, as soon as said dynamics expression tracker duct or ducts is or are exposed through an expression perforation or perforations in the music-sheet, it or they admit atmosphere under the corresponding pouch or pouches 35 lifting and seating the corresponding valves against the atmosphere ports 30 and connecting the exhaust via corresponding exhaust port or ports 31 with the related accordion compartment or compartments, immediately resulting in its or their collapse as will be well understood by those skilled in the art.

Fig. 1 shows the parts in what may be called their normal position with all dynamics tracker ducts 4^b closed and the accordion bellows fully expanded. This gives pianissimo playing with the regulator operating with its movable board 1^c in its lowest position and with the spring 38 exerting minimum pull on it. Further, it will be well understood by those skilled in the art that whenever expression perforations 4^b appear at the tracker bar, the corresponding accordion compartments collapse pulling the heel of the valve 6 downwardly against the tension of the spring 12, resulting in correspondingly louder regulated playing with the regulator working with its movable board 1^c in a higher position with increased tension of the spring 38 and with higher exhaust in the action and louder playing of any and all notes played.

For example, a crescendo can be produced starting with pianissimo when the accordion bellows is fully expanded as aforesaid, by collapsing its compartments individually and in combination by the registering of the related dynamics music-sheet perforations A, B, C and D, with the dynamics tracker ducts 4^b, said collapsing of the accordion compartments for said supposed crescendo being in the following order: (A) compart-

ment 15^a; (B) compartment 15^b; (C) compartments 15^a and 15^b; (D) compartments 15^c; (E) compartments 15^c and 15^a, and so on, as will be well understood, up to fortissimo, if desired. The aforesaid letters A, B, C, D, etc., have been correspondingly applied to Fig. 3 to indicate the particular dynamics perforation or combination of perforations that will produce the given effects.

10 At the aforesaid pianissimo setting with fully expanded accordion bellows, one or many notes can be played, but because the exhaust is then weakest, the full number of striker pneumatics may fail to collapse to sound their notes if, due to humidity or any other reason, the piano hammer actions or other working parts do not work as freely and as easily as they do when the instrument and its expression device were originally 20 adjusted at the factory. If this happens in an instrument equipped with my present invention, the user can at once remedy the defect by merely adjusting the pointer 23 (Fig. 1) slightly to the right. He should 25 do this while the instrument is playing the pianissimo passage in which the notes ciphered or did not play. He simply moves the pointer to the right and leaves it at the point of adjustment at which all of the notes 30 play pianissimo without ciphering. Ordinarily, a slight adjustment of the pointer will be sufficient to cause the wedge 20^a to adjust the lever 18, accordion bellows and heel of the valve 6 bodily to uncover more of 35 the port 2 to a slightly greater extent to sufficiently increase the wind tension in the player action to play all of the notes of the pianissimo passages without ciphering.

On the other hand, even if the instrument 40 does not cipher but plays perfectly at pianissimo, the device is usable with advantage to adapt the instrument at will to the room and the conditions under which it is used. Thus, for a large room or to hear the instrument 45 from a distance, or to use it for dancing, etc., the pointer 23 will be adjusted to that place on the scale which will make the softest passages in the music-rolls audible under the given conditions or for the given purpose.

50 The important advantage inheres in my device that the aforesaid adjustments do not involve limiting in any way the collapse and expansion of the accordion or expression bellows, either in whole or in part. On the 55 contrary, said expression device is at all times under the unhampered control and operation of the dynamics expression music-roll perforations, whatever these may be. This is an important advantage since the ordinary devices for controlling the degree of loudness 60 of playing of a reproducing piano usually limit or cramp the operation of the expression bellows or pneumatic.

What I claim is:

65 1. In a player piano, the combination of a

regulator of the knife valve type, said valve being adjustable across its port both by the regulator and independently thereof; a music-sheet controlled accordion bellows opposed by a spring operatively connected to said valve to adjust it across its port independently of the regulator; a movable support for said accordion bellows, said support being adjustable in the direction of adjusting the regulator valve across its port; and a hand control convenient to the user of the instrument operatively connected to said support for adjusting said accordion bellows, its support and connected regulator valve while the accordion bellows is in operation and without limiting the collapse and expansion of the accordion bellows either in whole or in part.

2. In a player piano, the combination of a regulator of the knife valve type, said valve being adjustable across its port both by the regulator and independently thereof; a music-sheet controlled accordion bellows opposed by a spring operatively connected to said valve to adjust it across its port independently of the regulator; a movable support for said accordion bellows, said support being adjustable in the direction of adjusting the regulator valve across its port; and means convenient to the user of the instrument and controllable at will operatively connected to adjust said valve across its port while the accordion bellows is in operation and without limiting the collapse and expansion of said bellows either in whole or in part.

3. In a player piano, the combination of a regulator of the sliding valve type, said valve being adjustable across its port both by the regulator and independently thereof; a music-sheet controlled pneumatic operatively connected to said valve to adjust it across its port independently of the operation of said valve by the regulator; and a hand-controlled device operable to adjust the position of said pneumatic bodily as an entirety and thereby adjust the connected regulator valve while said pneumatic is in operation.

4. In a player piano, the combination of a regulator and its valve, said valve being adjustable both by the regulator and independently thereof; music-sheet controlled means operatively connected with said regulator valve to adjust it independently of the operation of said valve by the regulator; and a hand controlled device operable to adjust the position of said music-sheet controlled means bodily as an entirety and thereby adjust the connected regulator valve while said means is in operation.

Signed at New York, in the county of New York and State of New York, this 16th day of May A. D. 1927.

JOSEPH H. DICKINSON.
